ALF ENGEBRETSEN, OF CHICAGO, ILLINOIS, ASSIGNOR TO JOSEPH ROSE, OF CHICAGO, ILLINOIS.

CARRIER-SELECTING DEVICE FOR PNEUMATIC-DESPATCH-TUBE APPARATUS.

1,383,194.

Specification of Letters Patent.

Patented June 28, 1921.

Application filed March 20, 1920. Serial No. 367,485.

To all whom it may concern:

Be it known that I, ALF ENGEBRETSEN, a citizen of the United States, residing at Chicago, in the county of Cook and State of Illinois, have invented new and useful Improvements in Carrier-Selecting Devices for Pneumatic-Despatch-Tube apparatus, of which the following is a full, clear, concise, and exact description, reference being had to the accompanying drawing, forming a part of this specification.

My invention relates to improvements in carrier selecting devices for pneumatic despatch tube apparatus, and has for its object the production of a device of this character which will be positive and dependable in operation and which will permit of the use of carriers which, though of two different classes, will all be of identical construction, the two classes differing from each other only in length.

A still further object is the provision of a carrier selecting device of the character mentioned which will be of durable and economical construction and highly efficient in operation.

Other objects will appear hereinafter.

With these objects in view the invention consists of the combinations and arrangements of parts hereinafter described and claimed.

The invention will be best understood by reference to the accompanying drawings forming a part of this specification, and in which—

Figure 1 is a partially sectional side elevation of a carrier selecting device for pneumatic despatch tube apparatus embodying the invention, this figure showing the discharge of one of the carriers of the short class;

Fig. 2 is a view similar to Fig. 1 showing the discharge of one of the carriers of the long class;

Fig. 3 is a partially sectional view of the device as viewed from a position at right angles to that seen in Figs. 1 and 2; and

Fig. 4 is a horizontal section taken on substantially line 4—4 of Fig. 2.

The preferred form of construction, as illustrates in the drawings, comprises a transmission tube 1 which, in the installation of practical employment of my device, will be a part of the pneumatic system in connection with which the device is used.

At the terminal of said tube is provided the carrier selecting device forming the subject matter of this application. This device comprises a split collar 2 which embraces the end of said tube 1, the same being secured thereto by means of a screw 3 which connects the ends of said collar.

Depending from the opposite sides of the collar 2 are two spaced elongated bars 4, the upper ends of which are secured by screws 5 to laterally projecting lugs 6 formed upon said collar. The lower ends of the bars 4 are secured by screws 7 to laterally projecting lugs 8 formed at opposite sides of an abutment member 9.

The carriers which are used in connection with my construction are adapted to be transmitted through the tube 1, the same being delivered by the latter to the receiver which is constituted by the parts 2, 4 and 9, where the same are brought to an abrupt stop through engagement of the forward end of each carrier with the abutment member 9.

Formed at the upper side of the member 9 is an inclined abutment surface 10 against which the forward end of each carrier impinges upon the delivery of the latter to the receiver, as above set forth. The arrangement of said abutment surface 10 is such, as will be seen, that the forward end of the carrier engages therewith at one side of said carrier or at one side of the longitudinal axis thereof with the result that said abutment surface in bringing the carrier to a stop will at the same time cause the same to be pitched or toppled toward one side of the receiver, that is, toward the right, as the device is illustrated in Figs. 1 and 2 of the drawings.

In order to prevent slipping or creeping of the forward end of the carrier upon the surface 10 in the engagement of the former with said surface, a transversely extending ridge or stop 11 is formed upon said surface for contact with said forward end of the carrier, as clearly seen in Figs. 1 and 2.

Carried by the collar 2 is an abutment member in the form of an elongated vertically extending finger 12, the upper end of which is positioned between two spaced vertically extending flanges 13 formed at one side of said collar. The flanges 13 are provided with spaced alining openings 14 adapted for engagement by a cotter pin 15 which is

adapted to support the member 12, the upper end of the latter being provided with looped portions 15' for engagement with said cotter pin.

5 By providing a plurality of spaced openings 14, it will be seen that provision is made for adjusting the vertical position of the member 12 relative to the carrier receiver. A spring 16 co-operates with the abutment member 12 to normally hold the free end thereof at its inner terminal of movement, that is, in a position in which the same rests against the adjacent side of collar 2.

The carriers which are used in connection 15 with this device are divided into classes A and B. All of these carriers are of identical construction, the only difference being in the length of the same, the carriers of class A being slightly shorter than the carriers of 20 class B. The arrangement is such that, in the delivery of the carriers to the receiver, they will all be first caused to topple in the same direction, that is, to the right, as seen in Figs. 1 and 2. The carriers of class 25 A, in thus being toppled, will be cause, by gravity, to be discharged from the receiver, the same simply toppling through or from the right side of the receiver, as seen in Fig. 1. The receivers of class B, however, because of the length thereof, in being toppled to the right, as seen in Figs. 1 and 2, will engage at their rearward or upper ends against the abutment member 12 which will yield slightly under the influence of the 30 carrier, and in rebounding will thrust the carrier in the opposite direction, as seen in Fig. 2, and thus cause the same to be discharged from the opposite side of the receiver. Thus it will be seen that the carriers will be automatically sorted, the carriers of class A, that is, the shorter carriers, being discharged from one side of the receiver, whereas the carriers of class B, that is, the longer carriers, will be discharged from the opposite side of the receiver. By reason of the adjustable mounting of the abutment member 12 provision is 40 made for accommodating carriers of various lengths, as will be readily understood.

45 50 In order to prevent injury to the carriers as the same are thus discharged from the receiver, the abutment member 9 is provided at opposite sides of the upper edge portion thereof with cushioning members 17. Said cushioning members 17 are simply strips of leather or other cushioning material which are fastened in place by metallic bands or strips 18 and co-operating screws 19, the upper edge portions of the 55 members 17 being exposed for contact with the sides of the carriers as the same topple toward one side or the other of the receiver, as will be readily understood.

In the sorting out or selecting of the two 60 65 types or classes of carriers, said classes are

separated so as to permit of the same being conducted to separate stations where the carriers of each class may be handled by individual operators. The advantage of thus sorting or separating the two classes of carriers resides in the fact that with this arrangement it becomes unnecessary for the operators handling the carriers to effect the selection or sorting of the carriers, such as would be necessary were all of the carriers 75 delivered to the same station or into the same receptacle.

The selecting device set forth is positive and dependable in operation, and because of its simplicity in construction, may be 80 manufactured at a low cost. The same is of further advantage by reason of the fact that the carriers which are employed in connection therewith may all be of identical construction except for a slight difference 85 in length. This permits of more economical manufacture of the carriers than would be possible did the two classes of carriers differ from each other in structural provisions.

While I have illustrated and described the 90 preferred form of construction for carrying my invention into effect, this is capable of variation and modification without departing from the spirit of the invention. I therefore do not wish to be limited to the 95 precise details of construction set forth, but desire to avail myself of such variations and modifications as come within the scope of the appended claims.

Having thus described my invention, what 100 I claim as new and desire to secure by Letters Patent is:

1. In pneumatic despatch tube apparatus, the combination of a transmission tube for carriers; a receiver to which the carriers are delivered by said tube; means for causing each carrier delivered to said receiver to topple over toward one side of said receiver; and means for causing certain of the carriers when so toppled, to be 105 engaged and caused to topple back in another direction.

2. In pneumatic despatch tube apparatus, the combination of a transmission tube for carriers; a receiver to which the carriers are 115 delivered by said tube; means for causing each carrier delivered to said receiver to topple over toward one side of said receiver; and resilient means for causing certain of the carriers when so toppled, to be engaged 120 and caused to topple back in another direction.

3. In pneumatic despatch tube apparatus, the combination of a transmission tube for carriers; a receiver to which the carriers are 125 delivered by said tube; means for causing each carrier delivered to said receiver to topple over toward one side of said receiver; and yieldable means for causing certain of the carriers when so toppled, to be engaged and 130

caused to topple back in another direction.

4. In a pneumatic despatch tube apparatus, the combination of carriers of two different lengths; a tube for the transmission of the carriers; a receiver to which the carriers are delivered by said tube; means for causing each carrier delivered to said receiver to topple over toward one side of said receiver; and means for causing the longer of said carriers when so toppled to be thrust back and toppled in another direction.

5. In pneumatic despatch tube apparatus, the combination of carriers of two different lengths; a tube for the transmission of the carriers; a receiver to which the carriers are delivered by said tube; means for engaging the forward end of each carrier delivered to said receiver to cause the carrier to topple over toward one side of said receiver; and means for engaging the rearward end of each of the longer carriers, when so toppled, to cause the same to be thrust back and topple in another direction.

6. In pneumatic despatch tube apparatus, the combination of carriers of two different lengths; a tube for the transmission of the carriers; a receiver to which the carriers are delivered by said tube; means for engaging the forward end of each carrier delivered to said receiver to cause the carrier to topple over toward one side of said receiver; and means for engaging the rearward end of each of the longer carriers, when so toppled, to cause the same to be thrust back and toppled in another direction, said last mentioned means being adjustable in a direction parallel with the longitudinal axis of said tube.

7. In pneumatic despatch tube apparatus, the combination of carriers of two different lengths; a tube for the transmission of the carriers; a receiver to which the carriers are delivered by said tube; means for engaging the forward end of each carrier delivered to said receiver to cause the carrier to topple over toward one side of said receiver; and a spring held member for engaging the rearward end of each of the longer carriers, when so toppled, to cause the same to be thrust back and topple in another direction.

8. In pneumatic despatch tube apparatus, the combination of carriers of two different lengths; a tube for the transmission of the carriers; a receiver to which the carriers are delivered by said tube; means for engaging the forward end of each carrier delivered to said receiver to cause the carrier to topple over toward one side of said receiver; a spring held member for engaging the rearward end of each of the longer carriers, when so toppled, to cause the same to be thrust back and topple in another direction.

rection; and fastening means for said spring held member permitting of adjustment of the position thereof in a direction parallel with the longitudinal axis of said tube.

9. In pneumatic despatch tube apparatus, the combination of carriers of two different lengths; a tube for the transmission of the carriers; a receiver to which the carriers are delivered by said tube; means for engaging the forward end of each carrier delivered to said receiver to cause the carrier to topple over toward one side of said receiver; a spring held member for engaging the rearward end of each of the longer carriers, when so toppled, to cause the same to be thrust back and toppled in another direction; and fastening means for said spring held member permitting of adjustment of the position thereof in a direction parallel with the longitudinal axis of said tube, said fastening means comprising a plurality of spaced openings; and a pin supporting said member and engagable with said openings.

10. In pneumatic despatch tube apparatus, the combination of a transmission tube for carriers; a receiver to which the carriers are delivered by said tube; an abutment in said receiver arranged for engagement with the forward end of each carrier at a point to one side of the longitudinal axis of the carrier, to effect toppling over of the carrier toward one side of said receiver; and means for causing certain of the carriers, when so toppled, to be engaged and toppled back in another direction.

11. In pneumatic despatch tube apparatus, the combination of a transmission tube for carriers; a receiver to which the carriers are delivered by said tube; an inclined abutment in said receiver arranged for engagement with the forward end of each carrier at a point to one side of the longitudinal axis of the carrier, to effect toppling over of the carrier toward one side of said receiver; means for causing certain of the carriers, when so toppled, to be engaged and toppled back in another direction; and means on said inclined abutment to prevent slipping thereon of the carrier engaging therewith.

12. In pneumatic despatch tube apparatus, the combination of a transmission tube for carriers; a receiver to which the carriers are delivered by said tube; an inclined abutment in said receiver arranged for engagement with the forward end of each carrier at a point to one side of the longitudinal axis of the carrier, to effect toppling over of the carrier toward one side of said receiver; means for causing certain of the carriers, when so toppled, to be engaged and toppled back in another direction; and a ridge on said inclined abutment to prevent slipping thereon of the carrier engaging therewith.

13. In pneumatic despatch tube apparatus,

the combination of a transmission tube for carriers; a receiver to which the carriers are delivered by said tube; means for causing carriers delivered to said receiver to topple over toward one side or the other of said receiver; and cushioning means detachably secured to said receiver against which the carriers engage in the toppling thereof.

14. In pneumatic despatch tube apparatus, the combination of a transmission tube for carriers; a receiver to which the carriers are

delivered by said tube; means for causing carriers delivered to said receiver to topple over toward one side or the other of said receiver; and an elongated strip of cushioning material having an exposed upper edge portion against which the receiver engages in the toppling thereof. 15

In witness whereof I have hereunto subscribed my name.

ALF ENGEBRETSEN.
